UNITED STATES PATENT OFFICE.

FRANK J. PETERSON, OF SWISSVALE, PENNSYLVANIA.

EXPANDING REAMER.

Application filed January 20, 1923. Serial No. 613,965.

To all whom it may concern:

Be it known that I, FRANK J. PETERSON, a citizen of the United States, residing at Swissvale, in the county of Allegheny and 5 State of Pennsylvania, have invented certain new and useful Improvements in Expanding Reamers, of which the following is a specification.

This invention is for an expanding 10 reamer of the type having separable segmental cutters.

The invention has for its principal object to provide an expanding reamer of a simple construction, which may be expanded to its limit with a relatively high degree of efficiency with respect to its normal or contracted status, and in which a very delicate and accurate expansion of the cutters may be effected, the cutters having 20 a fixed bearing surface on longitudinally movable members, whereby the cutters do not shift their point of contact with the supporting members according to any change of curvature which accompanies the 25 expanding and contracting movements.

The invention may be readily understood by reference to the accompanying drawings, in which:

Fig. 1 is a side elevation of the assembled 30 tool in a vertical position;

Fig. 2 is a side view, partly in section, of the tool, with the cutters or bits removed, showing the parts in the contracted position for the cutters;

Fig. 3 is a substantially similar view, 35 with the parts in expanded position;

Fig. 4 is a transverse section through the tool, with the cutters in contracted position;

Fig. 5 is a similar view, with the reamer 40 expanded;

Fig. 6 is a plan view of one end of one of the cutters or bits.

In the drawings, 5 designates a suitable 45 mandrel having a squared chuck engaging end 6 and a shank 7. The mandrel is threaded for a considerable portion of its length between its ends, as designated at 8. In the threaded portion of the mandrel, 50 are a plurality, preferably four, longitudi-

nally extending grooves 9 which increase in depth from one end toward the other.

Closely fitted into each groove is a key 10 which is tapered on its lower face to conform to the inclination of the bottom of the groove, the outer or top surface of each key preferably being slightly rounded. Each key is substantially shorter than the length of the groove, and formed at each end thereof is a barb 11 which slopes inwardly toward the ends of the key, an abrupt shoulder being provided at 12.

The keys are of the same width throughout, and are of such size that when they are received in the grooves with their thickest 65 portions in the deepest portions of the grooves, their surfaces, with the exception of the lugs or barbs 11, being substantially flush with the surface of the mandrel, as shown in Fig. 2. When they are moved 70 along the groove, however, the co-engaging inclined faces of the keys and grooves force them gradually outward, the outer faces of the keys always remaining parallel with the longitudinal axis of the mandrel.

The cutters or bits are designated 13, and are transversely curved, preferably to conform substantially to the outer surface of the mandrel. There are preferably four bits, and spiral teeth 14 are preferably provided on the outer surface, although other forms of teeth might, of course, be employed. Each end of the bits is beveled, as indicated at 15, and in the bevel portion is a longitudinal notch 16. The bits are of 80 substantially the same length as the keys, and when the bits are applied to the mandrel, the barbs or lugs 11 fit into the notches 16, and thus hold the bit from rotation relatively to the mandrel.

At each end of the keys and slidably on the mandrel is a sleeve 17 having a beveled recess 18 therein adapted to receive the beveled or tapered ends of the keys and bits, and thereby hold the parts assembled. Collars or nuts 19, threaded on the threaded part of the mandrel and having wrench engaging surfaces 20 thereon, serve to hold the sleeves in bit engaging and retaining position. By loosening the nut at one end of 100

the tool and tightening the other, the bits and keys may be moved longitudinally, thereby forcing the keys, and consequently the cutters, radially outwardly or inwardly.

It will be noted that the outer face of the keys has substantially the same curvature as the inner face of the bits. As there is no relative movement between the bits and 10 keys, the same surfaces are always in the same position of contact. The inner faces of the keys and of the grooves, being flat, or being of the same conformation throughout, the keys always have the same area 15 of contact with the bottoms of the grooves at all times. This is of considerable advantage over that form of expanding reamer where the curved inner surface of the cutter engages directly a slot in the 20 mandrel whose bottom is curved, because, in that form, the contacting surfaces conform when the cutters are in one position only, and as the cutters are shifted longitudinally to effect expansion or contraction, 25 the area of contact between the groove and the cutter changes.

The present device, furthermore, is a cheaper and more simple device to machine or manufacture.

30 I claim as my invention:

1. An expanding reamer comprising a mandrel having a series of longitudinal grooves therein whose depth increases from one end of the mandrel toward the other, a series of segmental longitudinally extending bits, and a key on the under face of each bit and movable therewith engaging in a groove in the mandrel and slideable therein to adjust the bits to different positions, and means for holding the parts in the different positions to which they are adjusted.

45 2. An expanding reamer comprising a mandrel having a series of longitudinal grooves therein whose depth increases from one end of the mandrel toward the other, a key slideable in each groove in the mandrel, a bit carried by each key and movable longitudinally therewith, means for adjustably retaining the keys and bits in place on the 50 mandrel, and means whereby rotative movement of the mandrel is positively transmitted to the bits.

55 3. An expanding reamer comprising a mandrel, a groove of gradually increasing depth in the mandrel, a key of gradually increasing thickness slideable in the groove, the taper of the key being reversed to that of the groove, a bit at whose inner surface the key is disposed and which is movable longitudinally with the key, said key and bit 60 being held against relative longitudinal and rotative movement, and means for adjustably retaining the key and bit in position on the mandrel.

65 4. An expanding reamer comprising a

mandrel having a groove of gradually increasing depth therein, a key of gradually increasing thickness slideable in the groove, said key having lugs at the ends thereof projecting above the surface of the key, a 70 bit resting on said key, which bit has notches therein to receive the lugs on the key for preventing relative movement between the key and bit, and means for adjustably retaining the key and bit in position on the mandrel. 75

5. An expanding reamer comprising a mandrel having a series of grooves of increasing depth therein, a key slideable in each groove, the keys also being of gradually increasing thickness and being so disposed in the groove that their outer surfaces are substantially parallel with the longitudinal axis of the mandrel, tapered lugs at the ends of the keys, a series of segmental bits resting on the keys and having notched tapered ends, the notches thereof receiving the lugs on the keys, and means adjustable longitudinally of the mandrel having a tapered recess for receiving the 80 tapered ends of the keys and bits for adjustably retaining the parts in position. 85

6. An expanding reamer comprising a mandrel, a series of detachable cutter segments, means interposed between the cutters and the mandrel having cooperating engagement with the cutters and mandrel and arranged to transmit motion from the mandrel to the cutter segments, said segments being longitudinally movable with 90 said means, said means being movable longitudinally along the mandrel and so engaged therewith as to move radially with such longitudinal movement to correspondingly move the cutter segments, and means for adjustably retaining the parts in position. 95

100 7. An expanding reamer comprising a mandrel having grooves of increasing depth therein by reason of which the bottoms of the grooves are inclined, a series of cutter bits having tapered ends, keys tapered reversely to the inclination of the grooves at the inner surface of the bits and engaging 105 in the grooves in the mandrel, said keys being attached to the bits and movable longitudinally therewith and adapted to move the cutter bits radially by longitudinal movement along said grooves, and means at each end of the bits having a tapered recess 110 therein for receiving the tapered ends of said cutter bits to retain said bits in position on the mandrel, said means being longitudinally adjustable on the mandrel to retain the parts in different adjusted positions. 115

120 8. An expanding reamer comprising a mandrel having a series of grooves of increasing depth therein, a key slideable in each groove, the keys also being of gradually increasing thickness and being so dis- 125

posed in the grooves that their outer surfaces are substantially parallel with the longitudinal axis of the mandrel, tapered lugs at the ends of the keys, a series of segmental bits resting on the keys and having notched tapered ends, the notches thereof receiving the lugs on the keys, a collar at each end of the cutters slidable on the man-

drel, said collars having tapered recesses therein for receiving the tapered ends of the cutters and keys and a nut disposed back of each collar and having a threaded engagement with the mandrel for adjustably retaining the parts in position.

It testimony whereof I affix my signature.
FRANK J. PETERSON.
